(57) CLAIM

I claim the ornamental design for a jeans with zippers, as shown and described.

DESCRIPTION

FIG. 1 is a front perspective view of jeans with zippers;

FIG. 2 is a front view of FIG. 1;

FIG. 3 is a rear view of FIG. 1; and,

FIG. 4 is a side view of FIG. 1.

The broken lines in FIGS. 1-4 represent stitching.
